UNITED STATES PATENT OFFICE.

ALFRED SMALLWOOD, OF HIGHGATE, LONDON, ENGLAND.

FURNACE.

1,403,202.

Specification of Letters Patent. Patented Jan. 10, 1922.

Application filed March 8, 1920. Serial No. 364,269.

To all whom it may concern:

Be it known that I, ALFRED SMALLWOOD, a subject of the Kingdom of Great Britain, residing at 42 Hargrave Park, Highgate, 5 London, N., in the county of Middlesex, England, metallurgist, have invented certain new and useful Improvements in or Relating to Furnaces, of which the following is a specification.

10 This invention comprises certain improvements in or relating to furnaces, and while being applicable to furnaces generally, the invention may, for example, be advantageously utilized for annealing of steel castings and production of malleable cast iron, pottery ware, sheet annealing, and the like.

According to the present invention I provide at intervals along the side or each side of the furnace, a series of flues or chambers 20 which communicate with the working chamber. These flues or chambers are adapted to receive gas, oil, vapor, powdered coal, or other appropriate fuel, and in conjunction with each vertical flue or chamber an air 25 admission port is provided whereby air, preferably recuperated, is supplied to the said gas so that the latter may mix and burn in the said flues or chambers, or when issuing therefrom into the working chamber. The supply of gas to the said flues or chambers may be individually regulable for each flue or chamber as may also the air 30 supply.

The waste gases advantageously egress 35 from the working chamber by way of a series of ports distributed over the floor. These ports may be arranged in series of longitudinal lines, the ports in the respective lines being staggered transversely of 40 the furnace.

In order that this invention may be clearly understood and readily carried into practice, reference may be had to the appended five sheets of explanatory drawings, 45 upon which:—

Figure 1 is an end sectional elevation of a furnace according to the present invention.

Figure 2 is a side vertical section of the 50 furnace shown in Figure 1, the plane of section being on the line 1—2 of the figure last mentioned.

Figure 3 is a sectional plan of the furnace 55 shown in Figures 1 and 2, the plane of section being on line 3—4 of Figure 1.

Figure 4 is an end sectional elevation of a modified furnace according to the present invention.

Figure 5 is a side sectional elevation of the furnace shown in Figure 4, the plane 60 of section being on line 5—6 of the figure last mentioned.

In a convenient embodiment of the present invention, and referring to Figures 1, 2 and 3, two gas producers *a* located at the 65 extremity of the furnace each communicate with a longitudinal green gas flue *b* running along the side of the furnace, and from the said green gas flue a series of up-shafts *c* extend at intervals along the side of the 70 furnace and communicate with the upper part of the working chamber *d*. Each up-shaft *c* is adapted to be individually regulated as for instance by a damper *e*.

At the level below that of the green gas 75 flues two recuperator systems are provided. Air enters at *f* and passes along a series of flues *g*. These flues communicate with other flues *h* along which the air flows in the reverse direction. From the flues *h* the air 80 passes into a flue *i* located below an arch above the recuperator system. From this flue a series of flues *j* extend at intervals along the length of the furnace and communicate with the respective up-shafts *c*. 85 As shown in Figure 2, for this purpose the flues *j* may be diverted laterally at *k*, and the laterally diverted parts thereof which communicate with the up-shafts *c* at *l* may be provided with control dampers *m*.

By this 90 arrangement the air and gas are brought together and allowed to mix and ignite before any absorption of heat takes place due to exposure to the goods. By providing for the individual regulation of the air and gas it is 95 possible to obtain oxidizing, reducing, or neutral furnace gases according to the class of work under treatment. It will be noted that the air follows a progressively ascending course, as a result of which its introduction is independent of any draught such as might have to be created by the stack; ingress of cold air as a result of draught suction is on this account eliminated.

Below the floor of the working chamber 105 and between the latter and the arches of the recuperators are four longitudinal waste gas flues *n*. Between these and the working chamber the egress floor ports *o* are provided. The method of supporting the work- 110

ing floor by the small arches of the waste gas flues *n* enables the said floor to withstand heavy loads, while the waste gases, while flowing within the flues *n*, are enabled to 5 radiate heat upwardly to the goods. The waste gas flues at one end of the furnace extend downwardly at *p* and communicate with longitudinal recuperator flues *q* located intermediately to the air flues of the recuperator, and said waste gases egress to the stack by a transverse flue *r* at the other extremity 10 of the furnace.

In a modified embodiment of the present invention as shown in Figures 4 and 5, a single gas producer communicates with one green gas flue *s*¹ from which up-shafts *c*¹ extend as in the previous embodiment. These up-shafts are located on one side only of the furnace. The air supply is similar to that 15 in the previous embodiment, air being admitted to the recuperator flues *t* which communicate with a common flue *i*¹ from which ports *j*¹ extend upwardly to a common longitudinal flue *u*. From this flue *u* a series of 20 ports *v* extend to the up-shafts *c*¹. These ports are individually regulable by dampers *w*. In this embodiment a series of outlets *x* may be provided along the other side of the furnace, these outlets being individually 25 regulable by dampers *z*. The said outlets *x* communicate with a waste gas flue *7* running longitudinally of the furnace below the working chamber and between the latter and the single recuperator system. At one extremity 30 this waste gas flue *7* is extended

downwardly and communicates with a transverse flue *8* which admits to the waste gas recuperator flues *9*.

What I claim as my invention and desire to secure by Letters Patent is:—

1. A furnace, including a working chamber, a series of flues, at the side of the furnace and communicating with the working chamber, said flues adapted to receive fuel, air admission ports for each flue, and a series 45 of ports distributed over the floor of said working chamber for the egress of waste gases.

2. A furnace, including a working chamber, a series of flues at the side of the furnace 50 and communicating with the working chamber, said flues adapted to receive fuel, and air admission ports for each flue, a series of ports distributed over the floor of said working chamber and a series of flues located below the floor of the working chamber.

3. A furnace, including a working chamber, a series of flues at the side of the furnace and communicating with the working chamber, said flues adapted to receive fuel, 60 and air admission ports for each flue, a series of ports distributed over the floor of said working chamber for the egress of waste gases, and a series of individually regulable outlets, provided along the other side of the 65 furnace.

In witness whereof I have hereunto set my hand.

ALFRED SMALLWOOD.
